UNITED STATES PATENT OFFICE.

CLARANCE J. SCHRACK, OF LONG BEACH, CALIFORNIA.

SILENCER.

1,287,458.

Specification of Letters Patent. Patented Dec. 10, 1918.

Application filed October 20, 1917. Serial No. 197,714.

To all whom it may concern:

Be it known that I, CLARANCE J. SCHRACK, a citizen of the United States, residing at Long Beach, in the county of Los Angeles and State of California, have invented a new and useful Silencer, of which the following is a specification.

This invention pertains to devices of the character designed for silencing exhaust gases.

An object of this invention is to produce a device of this character having maximum effectiveness and one from which, when excessive pressure of the gases occurs, relief of the excessive pressure will take place automatically.

Another object is to produce a silencer having a silencing head which can be thrown out of commission when it is desired to relieve the silencer of all back pressure so that the engine with which the silencer is connected will produce more power.

Another object is to make provision for adjustment of the silencer so that exhaust of the gases from various sizes of engines will take place without noise and without material back pressure.

The accompanying drawings illustrate the invention:

30 Figure 1 is a side elevation of a silencer embodying the invention.

Fig. 2 is a sectional elevation of the silencer in Fig. 1, the movable head being shown in closed position in solid lines and 35 in open position in broken lines.

Fig. 3 is an elevation partly in section on line x^2-x^3 , Fig. 2.

Fig. 4 is a sectional elevation on line x^4-x^5 , Fig. 2.

40 Fig. 5 is an enlarged side elevation of the adjustable valve.

There is provided an exhaust expansion chamber 1 of any suitable size and shape. Said chamber 1, in the instance shown in the drawings, is in the form of a cylinder having an open end or mouth forming an outlet 2 and said cylinder is provided at the end opposite to the outlet with a stationary head 3 having an inlet port 4 adapted to be connected with the exhaust pipe, not shown, of an internal combustion engine. The outlet 2 is provided with an annular beveled seat 5 to engage the annular beveled portion 6 of a hollow head 7. In the instance shown 55 in the drawings the seat 5 as formed by one

edge of a ring 8 fastened by rivets 9 to the exhaust chamber 1.

The ring 8 is provided with outstanding lugs or ears 10 embracing a head-operating member in the form of a bell crank lever 11 which is pivoted by a pin 12 to the ears 10. Thus it is clear that the head 7 is movably mounted in the outlet 2. One arm of the bell crank lever 11 is fastened by rivets 13 or equivalents to the head 7 and the other 65 arm of said lever may be provided with an operating rod 14 which may be extended to any convenient point for operation. When the silencer is used on an automobile the operating rod 14 will preferably be connected to the usual muffle cutout means of 70 the automobile, so as to be conveniently operated by the driver of the automobile.

The head 7 is yieldingly held in closed position on its seat 5 as in solid lines in Fig. 75 2 by means of a spring 15 attached to the outer arm of the bell crank lever. When the device is installed in position, the spring 15 will be connected to a suitable stationary support, not shown.

The head 7 is of any suitable shape and in this instance has a semispherical outer wall 16 and a frusto-conical inner wall 17 adjoining the semispherical wall. The interior of the head 7 is provided with a partition 18 separating the interior into two 80 chambers, a chamber 19 and a chamber 20. The frusto-conical wall 17 is provided with ports 21 opening into the chamber 19 and the partition 18 is provided with ports 22 85 90 which afford communication between the chambers 19, 20. The semispherical wall 16 is provided with an exhaust port 23 axially of the head. Screw-threaded into the frusto-conical wall 17 axially of the head 7 95 and into the partition 18 and projecting into the chamber 20 is an adjustable valve 24. In the instance shown in the drawings, the valve 24 is in the form of a cylinder open at its outer end and provided at its inner end with a head 25 whereby adjustment of the valve in or out may be made. When the valve has been adjusted to the desired position, a lock nut 26 on the valve may be turned up tight against the inner face of 100 the head 7 so as to prevent turning of the valve.

The valve 24 is provided with any desired number of longitudinally extending openings in the form of rectangular slots 27 110

which extend from adjacent the head 25 about two-thirds the length of the valve, more or less.

The head 25 is provided with a port 28 opening into the interior of the valve.

The valve 24 is provided with a partition 29 extending transversely of its bore so as to still further deflect the gases and cause silencing of the exhaust thereof. It is not absolutely necessary to the functioning of the device that it be constructed with the partition 29, but such construction is preferable.

In practice, assuming that the inlet 4 is connected to the exhaust port of an internal combustion engine, and that the head 7 is in closed position, as in Fig. 2, the exhaust gases will pass from the engine through the port 4 into the exhaust chamber 1 and will expand therein. Gases will pass through the ports 21 into the chamber 19 and through the port 28 and inner ends of the slots 27 into the interior of the valve 24, and gases will pass from the valve 24 into the chamber 20 and thence through the outlet 23 to the atmosphere. Some of the gases will pass from the chamber 19 through the ports 22 to the chamber 20 and thence through the outlet 23.

30 The valve 24 will preferably be adjusted so that the silencer head 7 will normally be held closed against the pressure of the gases in the chamber 1 by the spring 15. If for any reason excessive pressure of the exhaust gases should develop in the exhaust chamber 1, the pressure of said gases will open the head 7 outward against the tension of the spring 15 so that the gases can readily flow through the outlet 2 of the chamber 1 40 to relieve the pressure.

Adjustment of the valve 24 may be made to obtain different effects. For instance, screwing the valve 24 inward increases the areas of opening of both the inner portions 45 of the slots 27 and the outer portions thereof so that a greater volume of exhaust gases can flow from the chamber 1 without causing movement of the head 7; and screwing the valve 24 outward has the opposite effect 50 so that a less volume of the gases can flow from the chamber 1, in which event the consequent greater pressure becomes effective to move the head 7 to open position. Also adjustment of the valve in and out changes 55 the sum of the areas of opening of the inner and outer portions of the slots 27 relative to the sum of the areas of the ports 21 to change the back pressure of a portion of the gases against another portion, to alter the 60 muffling effect.

In order to obtain silencing of the exhaust gases to a less degree than produced when the head 7 is in closed position, the operator will swing the head 7 into the dotted position α , Fig. 2, whereupon the ex-

haust gases will expand in the exhaust chamber 1 and pass therefrom through the outlet 2. When the head 7 is in open position the sound of the exhaust will be muffled to some extent because of the gases expanding in the exhaust chamber 1.

In former constructions the muffle cutout is located between the engine and the silencer, but in this invention the muffle cutout constituted by the movable head 7 is located at the exhaust end of the silencer chamber so that even when the head is in open position some silencing effect is produced by the muffling effect of the exhaust chamber 1.

I claim:

1. A silencer comprising an expansion chamber having an inlet and an outlet, and a head movably mounted in the outlet, and adapted to be moved out of axial alinement with the outlet, said head being adapted to admit of the passage of gas therethrough.

2. A silencer comprising an expansion chamber having an inlet and an outlet, a head movably mounted in the outlet, and adapted to be moved out of axial alinement with the outlet, said head being adapted to admit of the passage of gas therethrough, and means yieldingly holding the head in closed position.

3. A silencer comprising an expansion chamber having an inlet and an outlet, and a pivotally mounted head at the outlet, said head being adapted to admit of the passage of gas therethrough.

4. A silencer comprising an expansion chamber having an inlet and an outlet, a pivotally mounted head at the outlet, said head being adapted to admit of the passage of gas therethrough, and means yieldingly holding the head in closed position.

5. A silencer comprising an expansion chamber having an inlet and an outlet, and a chambered head movably mounted in said outlet, there being ports through the inner wall of the head and an outlet in the outer wall of the head.

6. A silencer comprising an expansion chamber having an inlet and an outlet, a chambered head having an outlet and pivotally mounted in the outlet of the expansion chamber, and adjustable valve means to regulate the flow of gases from the expansion chamber to the chamber of the head.

7. A silencer comprising an expansion chamber having an inlet and an outlet, a chambered head having an outlet and movably mounted in the outlet of the expansion chamber, and adjustable valve means to regulate the flow of gases from the expansion chamber to the chamber of the head.

8. A silencer comprising an expansion chamber having an inlet and an outlet, a head movably mounted in the outlet of the expansion chamber, and adjustable valve means to regulate the flow of gases from the expansion chamber to the chamber of the head.

means in the head to control the flow of gases through the head.

9. A silencer comprising an expansion chamber having an inlet and an outlet, a hollow head pivotally mounted in the outlet and having a partition in its interior to separate the interior into two chambers, there being an outlet from one chamber of the head, ports opening through the partition, and other ports opening from the other chamber of the head to the exterior thereof.

10. A silencer comprising an expansion chamber having an inlet and an outlet, a hollow head movably mounted in the outlet and having a partition in its interior to separate the interior into two chambers, there being an outlet from one chamber of the head, ports opening through the partition, and other ports opening from the other chamber of the head to the exterior thereof.

11. A silencer comprising an expansion chamber having an inlet and an outlet, a hollow head mounted in the outlet and having a partition in its interior to separate the interior into two chambers, there being an outlet from one chamber of the head, and a tubular valve projecting from the expansion chamber side of the head through the partition and provided with longitudinally extending slots.

12. A silencer comprising an expansion chamber having an inlet and an outlet, a hollow head movably mounted in the outlet and having a partition in its interior to separate the interior into two chambers, there being an outlet from one chamber of the head, and a tubular valve projecting from the expansion chamber side of the head through the partition and provided with longitudinally extending slots.

13. A silencer comprising an expansion chamber having an inlet and an outlet, a hollow head mounted in the outlet and having a partition in its interior to separate

the interior into two chambers, there being an outlet from one chamber of the head, ports opening through the partition, other ports opening from the other chamber of the head to the exterior thereof, and a tubular valve projecting from the expansion chamber side of the head through the partition and provided with longitudinally extending slots.

14. A silencer comprising an expansion chamber having an inlet and an outlet, a hollow head movably mounted in the outlet and having a partition in its interior to separate the interior into two chambers, there being an outlet from one chamber of the head, ports opening through the partition, other ports opening from the other chamber of the head to the exterior thereof, and a tubular valve projecting from the expansion chamber side of the head through the partition and provided with longitudinally extending slots.

15. A silencer comprising an expansion chamber having an inlet and an outlet, movably mounted silencer means at the outlet end of the chamber, and means to move the silencer means away from the outlet.

16. A silencer comprising an expansion chamber having an inlet and an outlet, movably mounted silencer means at the outlet end of the chamber provided with a port open to the atmosphere at all times, and means to yieldingly hold the silencer means closed against the expansion chamber against relatively low pressures of gases in the expansion chamber, said last named means allowing the silencer means to be moved away from the chamber against higher pressure of the gases.

Signed at Los Angeles, California, this 6th day of October, 1917.
